UNITED STATES PATENT OFFICE.

WILLIAM A. BIGLER, OF CHICAGO, ILLINOIS.

DESIGN FOR A HANDLE FOR SPOONS, &c.

SPECIFICATION forming part of Design No. 22,035, dated December 6, 1892.

Application filed August 27, 1892. Serial No. 444,330. Term of patent 7 years.

To all whom it may concern:

Be it known that I, WILLIAM A. BIGLER, a citizen of the United States, residing at Chicago, in the county of Cook and State of Illinois, have invented and produced a new and original Design for the Handles of Spoons and Similar Articles, of which the following is a specification, reference being had to the accompanying drawing, which represents a spoon the handle of which embodies the design.

The leading and characteristic features of the present design are an eagle forming the end of the handle and the American flag laid in graceful folds and entwined around the handle, the eagle being perched and the wings partially spread, so as to give them graceful curved outlines that merge with the outline

of the entwined flag at the broad portion of the handle, and the flag being arranged with the star-spangled field at the broad part of the handle and beneath the eagle's feet.

A minor feature of the design is a streamer which the eagle holds in his beak. One end of the streamer falls across the eagle's breast, while the other end floats gracefully overhead, its lower edge touching the highest point of each of the wings.

What I claim is—

The design for the handles of spoons, &c., substantially as shown and described.

WILLIAM A. BIGLER.
